DESIGN FOR A CLASP

Jerome R. La Vigne, Waterbury, Conn., assignor
to The Waterbury Buckle Company, Water-
bury, Conn., a corporation of Connecticut

Application February 19, 1940, Serial No. 90,360

Term of patent 3½ years

to all whom it may concern:

Be it known that I, Jerome L. La Vigne, a citizen of the United States, residing at Waterbury, in the county of New Haven and State of Connecticut, have invented a new, original, and ornamental Design for a Clasp, of which the following a specification, reference being had to the accompanying drawing, forming part thereof.

Fig. 1 is a face view of a clasp showing my new design; and

Fig. 2 is a side view thereof.

The dominant feature of my new design comprises the central lever extending from a point adjacent the top of the body-portion of the clasp, below the said top, which extends thereover, to a point below the same.

I claim:

The ornamental design for a clasp, substantially as shown and described.

JEROME R. LA VIGNE.
